(57) CLAIM

We claim the ornamental design for a display box, as shown and described.

DESCRIPTION

FIG. 1 is a perspective view of a display box with a top lid in an open position, according to our new design;

FIG. 2 is a top plan internal view thereof, with lid removed for ease of illustration;

FIG. 3 is a side view thereof, with lid closed; and,

FIG. 4 is a front view thereof, with lid closed.
